UNITED STATES PATENT OFFICE.

FRITZ SCHEEREN, OF FORD CITY, PENNSYLVANIA.

WINDOW-SCREEN.

1,167,526.

Specification of Letters Patent. Patented Jan. 11, 1916.

Application filed February 25, 1915. Serial No. 10,561.

To all whom it may concern:

Be it known that I, FRITZ SCHEEREN, a citizen of the United States, residing at Ford City, in the county of Armstrong 5 and State of Pennsylvania, have invented certain new and useful Improvements in Window-Screens, of which the following is a specification.

This invention relates to window screens and has special reference to window screens of that type in which the screen is attached to the window sash and is mounted upon a roller disposed at the upper or lower end of the window frame.

15 This invention has for its object the provision of an improved construction whereby the screen may be readily applied to the window and will be out of the way so as not to interfere in any degree with the 20 ordinary adjustment of the sash.

25 The invention also seeks to provide improved means for fastening the screen to the sash and also to improve the means for maintaining the screen in a taut condition below or above the sash.

The several stated objects of the invention and such other incidental objects as will appear from the following description, are attained in the construction illustrated 30 in the accompanying drawings, and the invention resides in certain novel features which will be particularly pointed out in the claims following the description.

In the drawings Figure 1 is a vertical 35 section of a window, showing portions of each sash and illustrating screens connected with sashes in accordance with my invention, the sash cords and the guide pulleys for the same being omitted; Fig. 2 is a detail 40 horizontal section of a portion of the window frame and sashes; Fig. 3 is a detail perspective view, showing the manner in which the screen is attached to the sash; Fig. 4 is an enlarged vertical detail section, 45 showing one method of attaching the screen to the sash in windows which are already in place; Fig. 5 is a detail perspective view, showing parts of the structure illustrated in Fig. 4 detached but in their proper approximate positions. Fig. 6 is a detail perspective view of a portion of the screen 50 guide shown in Fig. 4; Fig. 7 is a view similar to Fig. 4, but showing a slightly different arrangement of the screen; Fig. 8 is a detail view of the roller; Fig. 9 is a detail perspective view of one end of the

roller; Fig. 10 is a detail perspective view of the end of the screen and the key which engages the same to connect it to the sash; Fig. 11 is a detail perspective view of the 60 device for winding the spring in the roller.

In carrying out my invention, when the screen is to be applied to windows at the time the same are placed in the building, I provide boxes 1 and 2, respectively, above 65 and below the window frame, the upper box being formed by inserting in the wall of the building a beam or plate 3 above the window lintel 4 and the lower box being provided by placing in the wall of the building a 70 plate or board 5 below the sill 6. The inner side of each box is closed by a door 7 adapted to swing into the room and held normally in closed position by any convenient form of latch, indicated at 8. The sashes, indicated at 9 and 10, are mounted in the window frame in the usual manner so as to slide between stops or beads 11 and fit against the jambs. In the lintel 4 and in the sill 6, I form slots 12 through which the 80 screens 13 may pass from the respective sashes to the rollers upon which the screens are wound. The slots 12 may be located as will be found most convenient and the lower slot 12 may be located in the central vertical 85 plane of the lower sash so as to distribute the strain equally to all parts of the sash. The upper slot 12, however, will ordinarily be located to one side of the central vertical plane of the sash in order to avoid interference of the screen with the sash cord pulley. Each screen is attached to and wound upon a roller 14 which is preferably mounted in brackets 15 secured within the respective box 1 or 2. These brackets 15 90 may be of any well known construction and may be secured directly to the lintel 4 or the sill 6, but ordinarily it will be found advisable to interpose blocks 16 between the sill 6 and the lower brackets. The screens 100 may be secured to the respective rollers by any well known devices and may be of any preferred material, but will ordinarily be formed of wire netting. That edge of the screen which is free of the roller is reinforced by a metal strip or cap 17 which should extend across the entire width of the screen and is adapted to fit snugly in groove 18 formed in the sash, this groove being formed in the upper end of the upper 110 sash and in the lower end of the lower sash, as will be readily understood. The cap or

reinforcing plate may conveniently be of U-shape in cross section so as to embrace the edge of the screen and it should fit snugly in the groove so as to frictionally engage the walls of the same and thereby relieve the strain upon the fastening devices. The said reinforcing plate or cap and the screen are provided with slots or openings 19 through which are inserted keys 20 which are fitted in grooves 21 in the sash, it being understood of course, that this construction is duplicated on the two sashes with the exception that the key will lie in an inclined plane in the lower sash, whereas in the upper sash it will lie in a horizontal plane inasmuch as the lower sash is shaped to conform to the inclination of the sill.

The key 20 is provided with an opening or recess 22 in one end which is adapted to receive a withdrawing tool when it is desired to release the screen from the sash and vertical movement of the key away from the sash is prevented by a keeper 23 which is secured in the sash and extends over the key, as shown most clearly in Fig. 3. As the key extends through the openings 19 and across the screen and is held to the sash by the keeper 23, it is evident that the screen will be securely attached to the sash and must follow the movements of the same, while at the same time the screen may be readily detached when so desired. The key is slightly below the surface of the sash, while the keeper is flush with the same and consequently the sash may be moved close against the lintel or the sill of the window frame.

The window screen will preferably be somewhat wider than the sash and its side edges will project beyond the side edges of the sash and extend into slots or grooves 24 formed in the jambs, as shown most clearly in Fig. 2. The screen may extend entirely through these slots into the weight boxes formed in the sides of the window frame or 45 may extend only partly therethrough, as illustrated, and if so desired a metal lining 25 may be inserted in the groove or slot so as to engage the edge of the screen. This construction effectually guides the screen in 50 its vertical movement and prevents buckling of the same so that it will be smooth and sightly at all times.

The rollers may be of any desired length corresponding to the width of the screen and 55 of the window frame in which they are mounted. The roller comprises an outer cylindrical body 26 to which the end of the screen is secured and one end of this cylindrical body 26 is bored out, as shown at 27, 60 to receive a spring-supporting rod 28. This rod 28 is preferably a wooden cylindrical pin having its inner end engaging a socket or recess 29 in the outer cylindrical body and having its outer end bored to receive a 65 pintle or trunnion member 30. A metal cap

31 is placed over the outer end of this pin 28 so as to prevent splitting of the same and the pintle or trunnion 30 is inserted through a central opening in the said cap and into the end of the pin 28, after which 70 it is secured by a transverse key or pin 32. The outer extremity of this pintle or trunnion is reduced and flat sided, as shown at 33, so that when it is engaged in the bearing bracket 15, it will be held against rotation. In the outer end of the cylinder 26, I 75 secure a cap 34 which bears against the end of the pin 28 and the cap 31 fitted thereon and is provided at its center with a reinforcement or hub 35, the said reinforcement 80 or hub and the said cap being rotatably mounted upon the pintle 30. The said cap is provided with an opening 36 through which the wire of the spring 37 may pass and it also carries a pin or stud 38 to which 85 the end of said wire may be secured. An outer collar or ring 39 is secured upon and around the end of the cylinder 26 so as to reinforce the same and prevent splitting thereof, the caps 34 and 39 together serving 90 to very materially strengthen the end of the roller. The spring 37 is wound around the pin 28 and has its inner end secured in a notch 40 in the inner end of said pin, while the outer portion of the spring is carried through the opening 36 in the cap 34 and then around the hub or reinforcement 35, the free end thereof being secured to the pin 38, as before stated. In order to prevent unwinding of the spring, while the roller is 100 being fitted in place and also to put the spring under the proper tension before it is mounted in its bearing brackets, I employ the key illustrated in Figs. 8 and 11. This key comprises a winding member 41 having 105 an angular opening 42 near one end which is adapted to engage the flat sided portion 33 of the pintle 30, and this opening may be open-ended, as indicated in Fig. 8, or may have a wall on all sides, as shown in Fig. 11. 110 Pivoted to the opposite end of the said winding member, is a lever and holding arm 43 which is provided with a tooth or spur 44 at its free end. After the winding member has been engaged upon the flat sided end 115 of the pintle 30, as illustrated in Fig. 8, the arm 43 is swung away from the roller and utilized as a handle to rotate the key and the pintle and thereby transmit motion to the pin or rod 28 which will serve to wind 120 the spring. After the spring has been placed under the desired tension, the arm 43 is swung over to the roller and the tooth or spur 44 is impressed in the material of the roller, as shown in Fig. 8, so as to lock the 125 roller to the pintle and, consequently, prevent unwinding of the spring. The key should be so placed upon the pintle that it will lie outside the bearing bracket when the roller is fitted in place so that it may then be 130

disengaged from the pintle without releasing the pintle from the bracket. It will be readily understood that this device positively prevents unwinding of the spring,

- 5 while the roller is being fitted in its bearings, and may be easily detached from the roller and withdrawn. In small windows, a single spring will be found sufficient and the spring may be either a right handed or left handed spring, as is obvious, the tension under which the spring is placed serving to hold the screen taut between the sash and the end of the window frame and tending to wind the screen on the roller. In very 10 large windows, it will be found advisable to employ two springs, one at each end of the roller and preferably one of the springs will be right handed while the other is left handed. In such event, of course, it will be necessary to employ a winding and holding 15 device at each end of the roller.

In Fig. 4, I have illustrated one method of applying the screen to a window in an old building or a building which is already 20 standing. It being manifestly impractical and expensive to tear out a part of the wall, so as to provide the boxes for the rollers, the brackets 45, which support the roller, are secured upon the inner sill 46 and a 25 housing 47 is secured upon the sill so as to extend over the roller and protect the same against injury and also add to the sightlessness of the window when equipped with the spring. The roller 48 may be fitted in 30 the bearing brackets 45 or may be fitted in notches cut into the jamb of the window and suitably shaped to hold the pintles or trunnions of the roller, as will be readily understood. The inner face of the sash is 35 recessed, as shown at 49, and hooks 50 are secured in the said recess to engage openings 51 formed in the cap 52 on the edge of the screen. It will thus be readily seen that as the sash is raised, the screen will 40 be drawn from the roller and will close the space between the lower edge of the sash and the top of the housing 47. To guard against buckling of the screen and hold the same smooth below the sash, I provide a 45 guide strip 53, the lower edge of which is bent inwardly to provide a slightly curved flange 54 and at the ends of which are formed lips 55 having perforations 56 therein, through which fastening devices may be 50 inserted into the window jambs. This guide strip will extend across the window immediately above the sill and will hold the screen smooth while permitting it to pass freely 55 between the guide and the sill, as will be readily understood. Inasmuch as the screen is held smooth by this guide, it will wind upon or unwind from the roller easily without any tendency to catch and drag. The screen for the upper sash will be arranged 60 in the same manner as the screen illustrated

and described for the lower sash, except that the bearings for the roller and the housing for the same will be secured to the under side of the lintel and at the outer side of the sash.

In Fig. 7, I show a slightly different arrangement for applying the screen to the lower sash of a window in a building which is already standing, it being understood that the screen for the upper sash is a duplicate 70 of the one shown, except that it is disposed at the outer side of the sash and below the lintel, whereas the drawing shows a screen mounted at the inner side of the sash and on the upper side of the sill. In this arrangement, the brackets 57 are secured upon the sill 58 and closer to the front or inner edge thereof than is the case in the arrangement shown in Fig. 4. The housing 59 is also mounted upon the sill and extends over the roller and to the sash. The jambs 60 are cut-away at their lower ends to provide horizontal grooves in which the screen 61 may run, and immediately adjacent the sash the upper walls of the said grooves are curved upwardly, as indicated at 62 so as to accommodate the flexing of the screen and also guide the same into a vertical plane and hold the same smooth when the sash is raised. The edge of the screen is reinforced by the plate or cap 63 and to the said plate or cap I secure tongues 64 which engage hooks or similar devices 65 set in the recess 66 in the sash. In the arrangement shown in Fig. 7, as well as 80 that shown in Fig. 4, the housing is provided at its lower inner edge with an inwardly extending flange or lip 67 which rests upon the upper surface of the sill and forms a steady support for the housing, and keepers 68 are driven into the sill so as to extend over the said flange, as clearly shown, and thereby retain the housing in place. These keepers or fastening devices 85 may be readily withdrawn when it is necessary to remove the housing for any purpose.

It is thought that the operation of the device will be readily understood from the foregoing description taken in connection with the accompanying drawings. The parts are all simple in their construction and are compactly arranged so that the improvements may be readily applied to any window without detracting from the sightlessness of the same or interfering in any manner with the ordinary use or adjustment thereof.

Having thus described the invention, what is claimed as new is:

1. The combination of a window sash having a groove formed in one end and having a keyway in the external surface of said end disposed at an angle to said groove and intersecting the same, a screen having 125 its edge inserted in said groove and pro-

vided with an opening adapted to register with said keyway, a key fitted in said keyway and extending through said opening, a keeper secured upon the sash over said 5 key, and means for maintaining the screen in a taut condition.

2. The combination of a window frame, a sash slidable therein, bearings upon the frame, a roller having pintles adapted to 10 engage said bearings, a spring connecting the pintle and the roller, and means for winding the spring and also locking the same to the roller whereby to prevent unwinding of the spring.

15 3. The combination of a window frame, a sash slidable therein, bearings upon the frame, a roller having pintles in its ends

adapted to engage said bearings, a screen secured to the roller and connected to the sash, a spring wound about the pintle and 20 having one end connected with the roller, and a key constructed to have angular engagement with the pintle whereby the spring may be wound and provided with a holding member adapted to engage the 25 roller whereby to lock the spring to the roller and prevent unwinding thereof.

In testimony whereof I affix my signature in presence of two witnesses.

FRITZ SCHEEREN. [L.S.]
